CLAIM

The ornamental design for a housing for lawn trimmers or the like, as shown and described.

DESCRIPTION

FIG. 1 is a perspective view of a housing for lawn trimmers or the like, showing our new design, the motor and wheels shown in broken lines are for illustrative purposes only and form no part of the claimed design;

FIG. 2 is a right side elevational view thereof;

FIG. 3 is a left side elevational view thereof;

FIG. 4 is a top plan view thereof;

FIG. 5 is a cross-sectional view taken along lines 5—5 in FIG. 4;

FIG. 6 is a rear elevational view thereof;

FIG. 7 is a front elevational view thereof;

FIG. 8 is a bottom plan view thereof.
